US009803902B2

(12) **United States Patent**
Pham

(10) **Patent No.:** **US 9,803,902 B2**
(45) **Date of Patent:** **Oct. 31, 2017**

(54) **SYSTEM FOR REFRIGERANT CHARGE
VERIFICATION USING TWO CONDENSER
COIL TEMPERATURES**

(71) Applicant: **Emerson Climate Technologies, Inc.**,
Sidney, OH (US)

(72) Inventor: **Hung M. Pham**, Dayton, OH (US)

(73) Assignee: **Emerson Climate Technologies, Inc.**,
Sidney, OH (US)

(*) Notice: Subject to any disclaimer, the term of this
patent is extended or adjusted under 35
U.S.C. 154(b) by 105 days.

(57) **ABSTRACT**

A charge-verification system for a circuit including a condenser having an inlet, an outlet, and a coil circuit tube extending between the inlet and the outlet is provided. The charge-verification system may include a first of coil temperature sensor located on the coil circuit tube a first distance from the inlet and a second of coil temperature sensor located on the coil circuit tube a second distance from the inlet. The charge-verification system may also include a controller receiving a first signal from the first temperature sensor indicative of a first temperature and a second signal from the second temperature sensor indicative of a second temperature. The controller may determine which of the first signal and the second signal is closer to an actual saturated condensing temperature of the condenser.

**SYSTEM FOR REFRIGERANT CHARGE
VERIFICATION USING TWO CONDENSER
COIL TEMPERATURES**

**CROSS-REFERENCE TO RELATED
APPLICATIONS**

This application claims the benefit of U.S. Provisional Application No. 61/789,913, filed on Mar. 15, 2013. The entire disclosure of the above application is incorporated herein by reference.

FIELD

The present disclosure relates to refrigeration systems and more specifically to a charge-verification system for use with a refrigeration system.

BACKGROUND

The statements in this section merely provide background information related to the present disclosure and may not constitute prior art.

Compressors are used in a wide variety of industrial and residential applications to circulate refrigerant within a refrigeration, heat pump, HVAC, or chiller system (generically referred to as "refrigeration systems") to provide a desired heating and/or cooling effect. In any of the foregoing systems, the compressor should provide consistent and efficient operation to ensure that the particular refrigeration system functions properly.

Refrigeration systems and associated compressors may include a protection system that selectively restricts power to the compressor to prevent operation of the compressor and associated components of the refrigeration system (i.e., evaporator, condenser, etc.) when conditions are unfavorable. The types of faults that may cause protection concerns include electrical, mechanical, and system faults. Electrical faults typically have a direct effect on an electrical motor associated with the compressor, while mechanical faults generally include faulty bearings or broken parts. Mechanical faults often raise a temperature of working components within the compressor and, thus, may cause malfunction of and possible damage to the compressor.

In addition to electrical and mechanical faults associated with the compressor, the compressor and refrigeration system components may be affected by system faults attributed to system conditions such as an adverse level of fluids (i.e., refrigerant) disposed within the system or a blocked-flow condition external to the compressor. Such system conditions may raise an internal compressor temperature or pressure to high levels, thereby damaging the compressor and causing system inefficiencies and/or failures.

SUMMARY

A charge-verification system for a circuit including a condenser having an inlet, an outlet, and a coil circuit tube extending between the inlet and the outlet is provided. The charge-verification system may include a first of coil temperature sensor located on the coil circuit tube a first distance from the inlet and a second of coil temperature sensor located on the coil circuit tube a second distance from the inlet. The charge-verification system may also include a controller receiving a first signal from the first temperature sensor indicative of a first temperature and a second signal from the second temperature sensor indicative of a second

2

temperature. The controller may determine which of the first signal and the second signal is closer to an actual saturated condensing temperature of the condenser.

A method of charge-verification of a circuit including a condenser having an inlet, an outlet, and a coil circuit tube extending between the inlet and the outlet is also provided. The method may include determining a first temperature of the coil circuit tube at a first distance from the inlet of the condenser, determining a second temperature of the coil circuit tube at a second distance from the inlet of the condenser, providing the first temperature to a controller, and providing the second temperature to the controller. The method may also include determining by the controller which of the first temperature and the second temperature is closer to an actual saturated condensing temperature of the condenser.

Further areas of applicability of the present disclosure will become apparent from the detailed description provided hereinafter. It should be understood that the detailed description and specific examples are intended for purposes of illustration only and are not intended to limit the scope of the disclosure.

BRIEF DESCRIPTION OF THE DRAWINGS

The drawings described herein are for illustration purposes only and are not intended to limit the scope of the present disclosure in any way. The present disclosure will become more fully understood from the detailed description and the accompanying drawings, wherein:

FIG. 1 is a schematic representation of charge-verification system in accordance with the principles of the present disclosure implemented in a refrigeration system;

FIG. 2 is a graph showing coil temperature versus a percentage position of the coil circuit length during a normal charge condition according to the present disclosure;

FIG. 3 is a graph showing coil temperature versus a percentage position of the coil circuit length during an overcharge condition according to the present disclosure;

FIG. 4 is a graph showing coil temperature versus a percentage position of the coil circuit length during an undercharge condition according to the present disclosure;

FIG. 5 is a graph showing coil temperature versus a percentage position of the coil circuit length for two coil temperature sensors mounted at approximately forty percent and seventy percent, respectively, of the coil circuit length according to the present disclosure;

FIG. 6 is a flow chart detailing operation of a charge-verification system according to the present disclosure;

FIG. 7 is a flow chart detailing operation of a charge-verification system according to the present disclosure;

FIG. 8 is a flow chart detailing operation of a device that may operate one or both of the charge-verification systems of FIGS. 6 and 7; and

FIG. 9 is a bar graph showing various combinations of condenser temperature difference (TD), subcooling (SC), and approach temperature (AT) at different temperature and refrigerant charge conditions.

DETAILED DESCRIPTION

Example embodiments will now be described more fully with reference to the accompanying drawings.

Example embodiments are provided so that this disclosure will be thorough and will fully convey the scope to those who are skilled in the art. Numerous specific details are set forth such as examples of specific components, devices, and

methods to provide a thorough understanding of embodiments of the present disclosure. It will be apparent to those skilled in the art that specific details need not be employed, that example embodiments may be embodied in many different forms, and that neither should be construed to limit the scope of the disclosure. In some example embodiments, well-known processes, well-known device structures, and well-known technologies are not described in detail.

The terminology used herein is for the purpose of describing particular example embodiments only and is not intended to be limiting. As used herein, the singular forms “a,” “an,” and “the” may be intended to include the plural forms as well, unless the context clearly indicates otherwise. The terms “comprises,” “comprising,” “including,” and “having,” are inclusive and therefore specify the presence of stated features, integers, steps, operations, elements, and/or components, but do not preclude the presence or addition of one or more other features, integers, steps, operations, elements, components, and/or groups thereof. The method steps, processes, and operations described herein are not to be construed as necessarily requiring their performance in the particular order discussed or illustrated, unless specifically identified as an order of performance. It is also to be understood that additional or alternative steps may be employed.

When an element or layer is referred to as being “on,” “engaged to,” “connected to,” or “coupled to” another element or layer, it may be directly on, engaged, connected or coupled to the other element or layer, or intervening elements or layers may be present. In contrast, when an element is referred to as being “directly on,” “directly engaged to,” “directly connected to,” or “directly coupled to” another element or layer, there may be no intervening elements or layers present. Other words used to describe the relationship between elements should be interpreted in a like fashion (e.g., “between” versus “directly between,” “adjacent” versus “directly adjacent,” etc.). As used herein, the term “and/or” includes any and all combinations of one or more of the associated listed items.

Although the terms first, second, third, etc. may be used herein to describe various elements, components, regions, layers and/or sections, these elements, components, regions, layers and/or sections should not be limited by these terms. These terms may be only used to distinguish one element, component, region, layer or section from another region, layer or section. Terms such as “first,” “second,” and other numerical terms when used herein do not imply a sequence or order unless clearly indicated by the context. Thus, a first element, component, region, layer or section discussed below could be termed a second element, component, region, layer or section without departing from the teachings of the example embodiments.

Spatially relative terms, such as “inner,” “outer,” “beneath,” “below,” “lower,” “above,” “upper,” and the like, may be used herein for ease of description to describe one element or feature’s relationship to another element(s) or feature(s) as illustrated in the figures. Spatially relative terms may be intended to encompass different orientations of the device in use or operation in addition to the orientation depicted in the figures. For example, if the device in the figures is turned over, elements described as “below” or “beneath” other elements or features would then be oriented “above” the other elements or features. Thus, the example term “below” can encompass both an orientation of above and below. The device may be otherwise oriented (rotated 90 degrees or at other orientations) and the spatially relative descriptors used herein interpreted accordingly.

With reference to FIG. 1, a charge-verification system 10 is provided. The charge-verification system 10 may be used in conjunction with a refrigeration system 12 including a compressor 14, a condenser 18, an evaporator 22, and an expansion valve 26. While the refrigeration system 12 is described and shown as including a compressor 14, a condenser 18, an evaporator 22, and an expansion valve 26, the refrigeration system 12 may include additional and/or alternative components. Further, the present disclosure is applicable to various types of refrigeration systems including, but not limited to, heating, ventilating, air conditioning (HVAC), heat pump, refrigeration, and chiller systems.

During operation of the refrigeration system 12, the compressor 14 circulates refrigerant generally between the condenser 18 and the evaporator 22 to produce a desired heating and/or cooling effect. Specifically, the compressor 14 receives refrigerant in vapor form through an inlet fitting 30 and compresses the refrigerant. The compressor 14 provides pressurized refrigerant in vapor form to the condenser 18 via a discharge fitting 34.

All or a portion of the pressurized refrigerant received from the compressor 14 may be converted into the liquid state within the condenser 18. Specifically, the condenser 18 transfers heat from the refrigerant to the surrounding air, thereby cooling the refrigerant. When the refrigerant vapor is cooled to a temperature that is less than a saturation temperature, the refrigerant changes state from a vapor to a liquid. The condenser 18 may include a condenser fan 38 that increases the rate of heat transfer away from the refrigerant by forcing air across a heat-exchanger coil associated with the condenser 18. The condenser fan 38 may be a variable-speed fan that is controlled by the charge-verification system 10 based on a cooling demand.

The refrigerant passes through the expansion valve 26 prior to reaching the evaporator 22. The expansion valve 26 expands the refrigerant prior to the refrigerant reaching the evaporator 22. A pressure drop caused by the expansion valve 26 may cause a portion of the liquefied refrigerant to change state from a liquid to a vapor. In this manner, the evaporator 22 may receive a mixture of vapor refrigerant and liquid refrigerant.

The refrigerant absorbs heat in the evaporator 22. Accordingly, liquid refrigerant disposed within the evaporator 22 changes state from a liquid to a vapor when warmed to a temperature that is greater than or equal to the saturation temperature of the refrigerant. The evaporator 22 may include an evaporator fan 42 that increases the rate of heat transfer to the refrigerant by forcing air across a heat-exchanger coil associated with the evaporator 22. The evaporator fan 42 may be a variable-speed fan that is controlled by the charge-verification system 10 based on a cooling demand.

As the liquid refrigerant absorbs heat, the ambient air disposed proximate to the evaporator 22 is cooled. The evaporator 22 may be disposed within a space to be cooled such as a building or refrigerated case where the cooling effect produced by the refrigerant absorbing heat is used to cool the space. The evaporator 22 may also be associated with a heat-pump refrigeration system where the evaporator 22 may be located remote from the building such that the cooling effect is lost to the atmosphere and the rejected heat generated by the condenser 18 is directed to the interior of a space to be heated.

A system controller 46 may be associated with the charge-verification system 10 and/or the compressor 14 and may monitor, control, protect, and/or diagnose the compressor 14 and/or the refrigeration system 12. The system controller 46

may utilize a series of sensors to determine both measured and non-measured operating parameters of the compressor 14 and/or the refrigeration system 12. While the system controller 46 is shown as being associated with the compressor 14, the system controller 46 could be located anywhere within or outside of the refrigeration system 12. The system controller 46 may use the non-measured operating parameters in conjunction with the measured operating parameters to monitor, control, protect, and/or diagnose the compressor 14 and/or the refrigeration system 12. Such non-measured operating parameters may also be used to check the sensors to validate the measured operating parameters and to determine a refrigerant charge level and/or a fault of the refrigeration system 12.

The system controller 46 may control the condenser fan 38 and the evaporator fan 42 such that operation of the condenser fan 38 and the evaporator fan 42 is coordinated with operation of the compressor 14. For example, the system controller 46 may control one or both fans 38, 42 to operate at a full or reduced speed depending on the output of the compressor 14.

The condenser 18, having an inlet 50 and an outlet 54, may further include a first coil temperature sensor 58 and a second coil temperature sensor 62 positioned on first and second heat-exchanger coil circuit tubes (not shown). The first coil temperature sensor 58 may be located within a first predetermined range of the coil circuit length from the condenser inlet 50. For example, the first coil temperature sensor 58 may be located at approximately forty percent of the coil circuit length from the condenser inlet 50 or at any location between thirty percent and fifty percent of the coil circuit length from the condenser inlet 50. The second coil temperature sensor 62 may be located within a second predetermined range of the coil circuit length from the condenser inlet 50. For example, the second coil temperature sensor 62 may be located at approximately seventy percent of the coil circuit length from the condenser inlet 50 or at any location between sixty percent and ninety percent of the coil circuit length from the condenser inlet 50. The first and second coil temperature sensors 58, 62 detect a temperature of the refrigerant circulating in the condenser 18 and may be used by the system controller 46 of the charge-verification system 10 to determine a saturated condensing temperature (SCT) of the refrigerant.

While the condenser 18 is illustrated as a Plate-Fin Heat Exchanger Coil, the present disclosure is applicable to other heat exchangers such as a smaller 5 mm microtube, a Microchannel, Spine-Fin Heat Exchanger Coils, or other heat exchangers known in the art. Further, the condensing coil may include various different parallel circuits with different heat exchanger designs. The first and second coil temperature sensors 58, 62 may be associated with any of the heat exchangers of the various parallel circuits.

A liquid-line temperature sensor 66 may be located along a conduit 70 extending between the condenser 18 and the expansion valve 26 and may provide an indication of a temperature of the liquid refrigerant within the refrigeration system 12 or liquid-line temperature (LLT) to the system controller 46. While the liquid-line temperature sensor 66 is described as being located along the conduit 70 extending between the condenser 18 and the expansion valve 26, the liquid-line temperature sensor 66 could alternatively be placed anywhere within the refrigeration system 12 that allows the liquid-line temperature sensor 66 to provide an indication of a temperature of liquid refrigerant within the refrigeration system 12 to the system controller 46.

An outdoor/ambient temperature sensor 74 may be located external to the compressor 14 and generally provides an indication of the outdoor/ambient temperature (OAT) adjacent to the compressor 14 and/or the charge-verification system 10. The outdoor/ambient temperature sensor 74 may be positioned adjacent to the compressor 14 such that the outdoor/ambient temperature sensor 74 is in close proximity to the system controller 46. Placing the outdoor/ambient temperature sensor 74 in close proximity to the compressor 14 provides the system controller 46 with a measure of the temperature generally adjacent to the compressor 14. While the outdoor/ambient temperature sensor 74 is described as being located adjacent to the compressor 14, the outdoor/ambient temperature sensor 74 could be placed anywhere within the refrigeration system 12 that allows the outdoor/ambient temperature sensor 74 to provide an indication of the outdoor/ambient temperature proximate to the compressor 14 to the system controller 46. Additionally, or alternatively, local weather data could be retrieved using the internet, for example, to determine ambient temperature.

The system controller 46 receives sensor data from the coil temperature sensors 58, 62, the liquid-line temperature sensor 66, and the outdoor/ambient temperature sensor 74 for use in controlling and diagnosing the refrigeration system 12 and/or the compressor 14. The system controller 46 may additionally use the sensor data from the respective sensors 58, 62, 66, and 74 to determine non-measured operating parameters of the refrigeration system 12 and/or the compressor 14 using the relationships shown in FIGS. 3, 4, 5, 6, and 7.

The system controller 46 determines which of the temperatures received from the first coil temperature sensor 58 and the second coil temperature sensor 62 is closer to the actual SCT and uses that sensor in conjunction with the temperature reading from the liquid-line temperature sensor 66 to determine a subcooling and the charge level of the refrigeration system 12, as will be described in greater detail below.

With particular reference to FIG. 2, a graph showing coil temperature versus a percentage position of the coil circuit length during a normal charge condition is illustrated. Upon exiting the condenser 18, approximately ten to twenty percent of the refrigerant is in a gaseous state or de-superheating phase, approximately ten to twenty percent of the refrigerant is in a liquid state or subcooling phase, and the remaining sixty to seventy percent of the refrigerant is in a liquid/vapor state or two-phase condensing state. The subcooling phase typically yields approximately ten degrees Fahrenheit (10° F.) subcooling and is considered a normal charge level.

When the charge-verification system 10 operates under normal charge conditions, placement of the temperature sensor on a coil circuit tube at approximately a midpoint of the condenser 18 provides the system controller 46 with an indication of the temperature of the condenser 18 that approximates the saturated condensing temperature and saturated condensing pressure. When the charge-verification system 10 is normally charged such that the refrigerant within the refrigeration system 12 is within +/-fifteen percent of an optimum-charge condition, the information detected by the temperature sensor positioned at approximately the midpoint of the coil circuit tube is closer to the actual SCT.

With particular reference to FIG. 3, a graph showing coil temperature versus a percentage position of the coil circuit length during an overcharge condition is illustrated. An overcharge condition may exist when the subcooling tem-

perature is greater than approximately thirty degrees Fahrenheit (30° F.). When the condenser 18 is in an overcharge state, the coil mid-point temperature may already be sub-cooled, thus providing a much lower value than actual SCT based on pressure. An excess amount of refrigerant may be disposed within the refrigeration system 12, as the refrigerant disposed within the condenser 18 changes state from a gas to a liquid before reaching the midpoint of the condenser 18.

The refrigerant exiting the compressor 14 and entering the condenser 18 is at a reduced temperature and may be in an approximately 40/60 gas/liquid mixture. The reduced-temperature refrigerant converts from the vapor state to the liquid state at an earlier point along the length of the condenser 18 and therefore may be at a partial or fully liquid state when the refrigerant approaches the temperature sensor disposed at the midpoint of the condenser 18. Because the refrigerant is at a lower temperature, the temperature sensor at the midpoint reports a temperature to the system controller 46 that is lower than the actual SCT.

When the refrigeration system 12 operates in the overcharge condition, the subcooled liquid phase increases and the reading of the second coil temperature sensor 62 may be lower than the reading of the first coil temperature sensor 58 because the tube where the second coil temperature sensor is located is subcooled compared to the tube where the first coil temperature sensor is located. Therefore, during an overcharge condition, the temperature from the first coil temperature sensor 58 is closer to the actual SCT than the temperature from the second coil temperature sensor 62.

With particular reference to FIG. 4, a graph showing coil temperature versus a percentage position of the coil circuit length during an undercharge condition is illustrated. An undercharge condition may exist when the subcooling temperature is less than zero degrees Fahrenheit (0° F.). When the condenser 18 is in an undercharge state, any coil circuit tube after approximately the twenty percent de-superheating phase adequately measures the actual SCT temperature because the remaining portion of the condenser 18 is in two-phase condensing without any subcooled liquid phase.

When the refrigeration system 12 operates in the undercharge condition, the subcooled liquid phase decreases and the reading of the second coil temperature sensor 62 may approach the reading of the outlet liquid-line temperature sensor 66. Eventually, when the subcooling phase disappears because both sensors 58, 62 are detecting only the condensing phase, the readings of temperature sensors 58, 62 are approximately equal. In this situation, the temperature from the first coil temperature sensor 58 approximately equals the temperature from the second coil temperature sensor 62, which, in turn, approximates the actual SCT.

With reference to FIG. 5, a graph showing coil temperature versus a percentage position of the coil circuit length is illustrated. The positions of the first and second coil temperature sensors 58, 62 along a length of the condenser 18 are schematically represented by vertical lines at approximately thirty percent (30%) and seventy percent (70%), respectively. Each plotted line on the graph represents a different charge condition. Intersection between the plotted lines and the respective vertical lines of the first and second coil temperature sensors 58, 62 may be used by the controller 46 to identify amongst the various charge conditions.

In the condensing phase, the temperature changes mainly as a function of pressure drop; thus, the temperature changes very gradually, at approximately less than three degrees (3° F.) per coil circuit. When in the subcooled phase, the

temperature changes much more rapidly, at approximately greater than ten degrees (10° F.) per coil circuit.

When the temperature from the first coil temperature sensor 58 is greater than the temperature from the second coil temperature 62 sensor plus approximately two degrees Fahrenheit (2° F.) and both are greater than the LLT plus approximately seven degrees Fahrenheit (7° F.) ($T_{coil1} > T_{coil2} + 2^\circ F. > LLT + 7^\circ F.$), a normal charge condition is declared. When the temperature from the first coil temperature sensor 58 is approximately equal to the temperature from the second coil temperature sensor 62—which is approximately equal to the LLT ($T_{coil1} \approx T_{coil2} \approx LLT$)—an undercharge condition is declared; indicating that refrigerant should be added to the system. When the temperature from the first coil temperature sensor 58 is greater than the temperature from the second coil temperature sensor 62 plus approximately five degrees Fahrenheit (5° F.) and both are greater than the LLT plus approximately two degrees Fahrenheit (2° F.) ($T_{coil1} > T_{coil2} + 5^\circ F. > LLT + 2^\circ F.$), an overcharge condition is declared; indicating that refrigerant should be removed from the system.

For example, when the refrigeration system 12 is operating in an undercharged condition, the first coil temperature sensor 58 may be reporting eighty-four degrees Fahrenheit (84° F.), eighty-nine degrees Fahrenheit (89° F.), or ninety-five degrees Fahrenheit (95° F.) and the second coil temperature sensor 62 may be reporting eighty-three degrees Fahrenheit (83° F.), eighty-nine degrees Fahrenheit (89° F.), or ninety-four degrees Fahrenheit (94° F.). If the first coil temperature sensor 58 is reporting eighty-four degrees Fahrenheit (84° F.) and the second coil temperature sensor 62 is reporting eighty-three degrees Fahrenheit (83° F.), the subcooling temperature is 3.2° F. If the first coil temperature sensor 58 is reporting eighty-nine degrees Fahrenheit (89° F.) and the second coil temperature sensor 62 is reporting eighty-nine degrees Fahrenheit (89° F.), the subcooling temperature is 0.7° F. If the first coil temperature sensor 58 is reporting ninety-five degrees Fahrenheit (95° F.) and the second coil temperature sensor 62 is reporting ninety-four degrees Fahrenheit (94° F.), the subcooling temperature is 0.3° F. The graph illustrates similar relations for normal operation and overcharged operation as well. The controller 46 may therefore use the data from the first coil temperature sensor 58 and the second coil temperature sensor 62 along with the LLT to diagnose the charge level of the system.

Based on the temperature readings from the first and second coil temperature sensors 58, 62, the system controller 46 determines the subcooling temperature and the charge condition (as shown in FIG. 5). Based on the subcooling temperature and the charge condition, the system controller 46 may determine remedial actions that may be necessary, such as addition of refrigerant to the system or removal of refrigerant from the system.

Dependent upon the amount of refrigerant that needs to be added or removed from the system, the refrigerant may be added or removed in a series of incremental additions or removals to ensure that too much refrigerant is not added or removed. Between each of the series of incremental additions or removals, the system controller 46 may determine the subcooling temperature and the charge condition.

Now referring to FIG. 6, a charge verification method 100 is illustrated. The charge verification method 100 may be performed by the controller 46 during operation of the refrigeration system 12.

At 104, the method 100 determines whether the T_{coil1} equals the T_{coil2} and whether both of these values are approximately equal to the LLT ($T_{coil1} = T_{coil2} = LLT$). If

true, the method 100 determines that the refrigeration system 12 is operating in an undercharged condition at 106. At step 108, the method 100 recommends adding refrigerant to the system. The method 100 then returns to step 104 to continue evaluating the Tcoil1, the Tcoil2, and the LLT.

If false at step 104, the method 100 determines whether a first coil temperature (Tcoil1) is greater than a second coil temperature (Tcoil2) plus approximately two degrees Fahrenheit (2° F.) and whether both of these values are greater than the LLT plus approximately seven degrees Fahrenheit (7° F.) (Tcoil1>Tcoil2+2° F.>LLT+7° F.) at 110. If true, the method 100 determines that the refrigeration system 12 is operating in a normal charge condition at 112. The method 100 returns to step 104 to continue evaluating the Tcoil1, the Tcoil2, and the LLT.

If false at step 104, the method 100 moves to step 110 and if false at step 110, the method 100 moves to step 114 and determines whether the Tcoil1 is greater than the Tcoil2 plus approximately five degrees Fahrenheit (5° F.) and whether both of these are greater than the LLT plus approximately two degrees Fahrenheit (2° F.) (Tcoil1>Tcoil2+5° F.>LLT+2° F.). If true, the method 100 determines that the refrigeration system 12 is operating in an overcharged condition at 116. At 118, the method 100 recommends removing refrigerant from the system. The method 100 then returns to step 104 to continue evaluating the Tcoil1, the Tcoil2, and the LLT.

If false at step 114, the method 100 returns to step 104 to continue evaluating the Tcoil1, the Tcoil2, and the LLT.

With particular reference to FIG. 7, another charge-verification method 120 is provided. As with the charge-verification method 100, the charge-verification method 120 may be performed by the controller 46 during operation of the refrigeration system 12.

The charge-verification method 120 may be used by the controller 46 in conjunction with or in place of the charge-verification method 100 when determining the charge of the refrigeration system 12. If the methods 100, 120 are used in conjunction with one another, the methods 100, 120 may independently determine the charge of the refrigeration system 12 (i.e., normal charge, undercharge, or overcharge) and may be used by the controller 46 to verify the results of each method 100, 120. Namely, the result obtained by one of the methods 100, 120 may be used by the controller 46 to verify the result obtained by the other method 100, 120 by comparing the results obtained via each method 100, 120.

At 122, the method 120 determines whether the TD is less than approximately 0.75Y (i.e., 75% of Y) and whether a ratio of AT/TD is greater than approximately 90%, whereby the variable (Y) represents a predetermined desired TD value, which may be determined based on system efficiency. If true, the method 120 determines that the refrigeration system 12 is operating in an undercharged condition at 124. At step 126, the method 120 recommends adding refrigerant to the system. The method 120 then returns to step 122 to continue evaluating the system 12.

If false at step 122, the method 120 moves to step 128 and determines whether the TD is approximately equal to the predetermined desired TD value Y (i.e., +/-15% of Y) and whether the ratio of SC/TD is less than approximately 75%. If true, the method 120 determines that the refrigeration system 12 is operating in a normal charge condition at 130. The method 120 returns to step 122 to continue evaluating the system 12.

If false at step 122, the method 120 moves to step 128 and if false at step 128, the method 120 moves to step 132 and determines whether the TD is greater than approximately

1.5Y and whether a ratio of SC/TD is greater than approximately 90%. If true, the method 120 determines that the refrigeration system 12 is operating in an overcharged condition at 134. At 136, the method 120 recommends removing refrigerant from the system. The method 120 then returns to step 122 to continue evaluating the system 12.

If false at step 132, the method 120 returns to step 122 to continue evaluating the system 12.

The controller 46 may execute the foregoing methods 100, 120 simultaneously. Further, while the controller 46 monitors the system 12 for the undercharge condition prior to the normal-charge condition and the overcharge condition, the controller 46 could perform operations 104, 110, 114 of method 100 and operations 122, 128, 132 of method 120 in any order. The controller 46 is only described as performing operations 104 and 122 first, as most commercial refrigeration systems 12 are manufactured and shipped with a small volume of refrigerant and, therefore, are typically in the undercharge condition when initially installed.

In another configuration, the system controller 46 may additionally determine faults in the refrigeration system 12 along with determining the subcooling temperature and the charge condition. For example, the system controller 46 may determine a temperature difference (TD) between the SCT and the OAT (TD=SCT-OAT). The TD increases with an overcharge condition and decreases with an undercharge condition. The system controller 46 may further determine an approach temperature (AT) by subtracting the OAT from the LLT (AT=LLT-OAT). The AT decreases with an overcharge condition and increases with an undercharge condition.

Based on the foregoing, the system controller 46 is able to determine a refrigerant charge level and/or a fault by analyzing the AT, the TD and the SC without requiring additional temperature sensors (as illustrated in FIG. 1). Further, because the TD is equivalent to the SC plus the AT (TD=SC+AT), the percent split or ratio between the SC and the AT (making up the TD) is a good indicator of which fault is occurring.

For overcharge conditions, the TD is high, but the AT is small, thus an SC/TD ratio is greater than approximately ninety percent (90%). For undercharge conditions, the TD is low and the SC is low, thus an AT/TD ratio is greater than approximately ninety percent (90%). Accordingly, the controller 46 may differentiate between other faults as well, as described in detail below.

With particular reference to FIG. 9, a bar graph detailing different refrigerant charge conditions and other faults for the refrigeration system 12 is provided. Each bar in the graph illustrates the values and/or the relationship among TD, SC, and/or AT for different conditions. For example, the normal charge condition may be declared by the system controller 46 when the following conditions are true: AT=5° F., SC=15° F., and TD=AT+SC=20° F.

When diagnosing faults in the system, the system controller 46 may perform additional calculations to assist in the diagnosis. For example, the system controller 46 may utilize other data that signifies a particular operating condition to allow the controller 46 to differentiate amongst faults having similar characteristics. For example, the TDs for a one hundred thirty percent (130%) charge (overcharge) condition and a low condenser air flow condition (dirty coil) are both high (for example only, 35° F.). In order to differentiate between these two faults, the system controller 46 may determine a ratio of SC to TD. The controller 46 may declare an overcharge condition when SC/TD is greater than approximately ninety percent (90%), and may declare a low

11

condenser air flow fault (e.g. blocked or dirty condenser coil or condenser fan fault) when SC/TD is less than approximately ninety percent (90%).

The TDs for both a seventy-five percent (75%) charge (undercharge) condition and a thermal expansion valve (TXV) flow control restriction are low (for example only, 14° F. and 13° F., respectively). In order to differentiate between these two faults, the system controller 46 may determine a ratio of AT to TD. The undercharge condition may be declared when the ratio of AT/TD is greater than approximately ninety percent (90%) and the TXV fault may be declared when the ratio of AT/TD is less than approximately ten percent (10%).

As previously described, the coil temperature sensors 58, 62 may be used to determine the charge condition of the refrigeration system 12. This information may be useful when installing a new refrigeration system 12 or, alternatively, when monitoring or charging an existing system 12 following maintenance. In one configuration, the temperature sensors 58, 62 may be used in conjunction with an algorithm that utilizes information from the temperature sensors 58, 62 to aid in providing the refrigeration system 12 with the proper amount of refrigerant.

The algorithm may be performed by a computer such as, for example, a hand-held device or a laptop computer (FIG. 8). The computing device may prompt the installer to first select a line length of a refrigeration line set and a diameter of the line set at 140. For example, the line length and diameter may respectively be forty feet and three-eighths of an inch

$$\left(40 \frac{1}{32} \text{ ft}\right)$$

The installer may power on the system and wait approximately fifteen minutes or until the system controller 46 indicates that the system is stable for charging at 142. Because the factory charge is intended for only fifteen feet (15 ft) of refrigeration line, this particular unit may be undercharged, as described at 144. Thus, both the temperature reading from the first coil temperature sensor 58 and the temperature reading from the second coil temperature sensor 62 are valid SCTs in this situation. The controller 46 may calculate the SC using the formula $SC = SCT - LLT$ and confirm whether approximately two degrees Fahrenheit is less than the SC and whether the SC is less than a target SC (2° F. < SC < SCtarget) at 146, where the target SC is approximately ten degrees Fahrenheit (10° F.). If the target SC is provided from original equipment manufacturer data, the system controller 46 will use this as the target SC instead.

The system controller 46 may calculate and display an amount of charge (X) to be added at 148. The system controller may prompt the installer to add X charge to the system at 150 (if X is large, the addition may be performed in a plurality of increments). The system controller 46 may check for system stabilization and may display the SC versus the target SC on the computing device at 152. When the SC is approximately equal to the target SC, the system controller 46 may indicate that the charge is complete at 154. If the installer adds more charge than requested by the system controller 46, the system controller 46 may determine an overcharge condition and may prompt the installer to recover and start the charge process again at 156.

The charge-verification system 10 and method 100 may also be applied to a split heat pump operating in a heating

12

mode if both the first coil temperature sensor 58 and the second coil temperature sensor 62 are positioned on the indoor coil of the heat pump system. The SCT determined may be used to calculate a Discharge Superheat (DSH). 5 Further, the charge-verification system 10 and method 100 are intended for both initial installation as well as on-going monitoring and maintenance service of the refrigeration system 12.

The foregoing description of the embodiments has been 10 provided for purposes of illustration and description. It is not intended to be exhaustive or to limit the disclosure. Individual elements or features of a particular embodiment are generally not limited to that particular embodiment, but, where applicable, are interchangeable and can be used in a 15 selected embodiment, even if not specifically shown or described. The same may also be varied in many ways. Such variations are not to be regarded as a departure from the disclosure, and all such modifications are intended to be included within the scope of the disclosure.

20 Those skilled in the art may now appreciate from the foregoing that the broad teachings of the present disclosure may be implemented in a variety of forms. Therefore, while this disclosure has been described in connection with particular examples thereof, the true scope of the disclosure should not be so limited since other modifications will become apparent to the skilled practitioner upon a study of the drawings, the specification and the following claims.

What is claimed is:

1. A charge-verification system for a circuit including a 30 compressor and a condenser having an inlet, an outlet, and a coil circuit tube extending between the inlet and the outlet, the charge-verification system comprising:

a first temperature sensor located on said coil circuit tube
a first distance from said inlet;

a second temperature sensor located on said coil circuit tube
a second distance from said inlet;

a controller receiving a first signal from said first temperature sensor indicative of a first temperature and receiving a second signal from said second temperature sensor indicative of a second temperature, said controller determining which of said first signal and said second signal is closer to an actual saturated condensing temperature of the condenser; and

a liquid line temperature sensor providing a signal to said controller indicative of a liquid temperature of a liquid circulating within the circuit,

wherein said controller controls the compressor based on 40 one of said first signal and said second signal, and said controller determines a charge condition based on a comparison of at least two of the first temperature, the second temperature, and the liquid temperature.

2. The system of claim 1, wherein said one of said first signal and said second signal is closer to said actual saturated condensing temperature than the other of said first signal and said second signal.

3. The system of claim 1, wherein said first distance is approximately thirty to fifty percent of a total length of the coil circuit tube.

4. The system of claim 3, wherein said first distance is 50 approximately forty percent of said total length of the coil circuit tube.

5. The system of claim 3, wherein said second distance is approximately sixty to ninety percent of said total length of the coil circuit tube.

6. The system of claim 5, wherein said second distance is approximately seventy percent of said total length of the coil circuit tube.

13

7. The system of claim 1, wherein said controller determines a normal charge condition when said first temperature is greater than said second temperature plus approximately two degrees Fahrenheit and both of said first temperature and said second temperature are greater than said liquid temperature plus approximately seven degrees Fahrenheit.

8. The system of claim 1, wherein said controller determines an overcharge condition when said first temperature is greater than said second temperature plus approximately five degrees Fahrenheit and both of said first temperature and said second temperature are greater than said liquid temperature plus approximately two degrees Fahrenheit.

9. The system of claim 1, wherein said controller determines an undercharge condition when said first temperature is approximately equal to said second temperature.

10. The system of claim 9, wherein said second temperature is approximately equal to said liquid temperature.

11. A method of charge-verification by a controller of a circuit including a condenser having an inlet, an outlet, and a coil circuit tube extending between the inlet and the outlet, the method comprising:

processing, by the controller, a first temperature of the coil circuit tube at a first distance from the inlet of the condenser;

processing, by the controller, a second temperature of the coil circuit tube at a second distance from the inlet of the condenser;

processing, by the controller, a liquid temperature of a liquid circulating within the circuit;

determining, by the controller, which of said first temperature and said second temperature is closer to an actual saturated condensing temperature of the condenser; and

determining, by the controller, a charge condition based on a comparison of at least two of the first temperature, the second temperature, and the liquid temperature.

14

12. The method of claim 11, further comprising controlling a compressor based on one of said first temperature and said second temperature.

13. The method of claim 12, wherein said one of said first temperature and said second temperature is closer to said actual saturated condensing temperature than the other of said first temperature and said second temperature.

14. The method of claim 11, wherein determining said first temperature at said first distance includes determining said first temperature at a first location from the inlet that is approximately thirty to fifty percent of a total length of the coil circuit tube.

15. The method of claim 14, wherein determining said second temperature at said second distance includes determining said second temperature at a second location from the inlet that is approximately sixty to ninety percent of said total length of the coil circuit tube.

16. The method of claim 11, further comprising determining by said controller a normal charge condition when said first temperature is greater than said second temperature plus approximately two degrees Fahrenheit and both of said first temperature and said second temperature are greater than said liquid temperature plus approximately seven degrees Fahrenheit.

17. The method of claim 11, further comprising determining by said controller an overcharge condition when said first temperature is greater than said second temperature plus approximately five degrees Fahrenheit and both of said first temperature and said second temperature are greater than said liquid temperature plus approximately two degrees Fahrenheit.

18. The method of claim 11, further comprising determining by said controller an undercharge condition when said first temperature is approximately equal to said second temperature.

19. A controller performing the method of claim 11.
